(57) **CLAIM**

The ornamental design for a nail buffer, as shown and described.

DESCRIPTION

FIG. 1 is a perspective view of a nail buffer in accordance with my invention;

FIG. 2 is a left side elevation view of the nail buffer shown in FIG. 1;

FIG. 3 is a right side elevation view of the nail buffer shown in FIG. 1;

FIG. 4 is an end elevation view of the nail buffer shown in FIG. 1;

FIG. 5 is an opposite end elevation view of the nail buffer shown in FIG. 1;

FIG. 6 is a top plan view of the nail buffer shown in FIG. 1; and,

FIG. 7 is a bottom plan view of the nail buffer shown in FIG. 1.

The indicia shown in broken lines in FIGS. 1 and 6 is for illustrative purposes only and forms no part of the claimed design.
